UNITED STATES PATENT OFFICE

ANTON BREZINSKI, OF PERTH AMBOY, NEW JERSEY

WINDOW PANE RETAINING STRIP

Application filed November 15, 1932. Serial No. 642,705.

This invention relates to improvements in window pane fastening means, and has particular reference to a retaining strip therefor.

5 The primary object of the invention resides in a permanent window pane retaining strip to be used in lieu of putty and which is sealed against the glass pane and the sash frame when secured in position to prevent 10 leakage of the elements to the inside of the window.

Another feature of the invention is the provision of a flexible extensible glass pane retaining strip which may be bent to conform 15 to the shape of the sash frame and lengthened by pulling thereon without distorting its cross sectional configuration to accurately fit into position should the length be cut too short.

20 A further object of the invention is to provide a soft malleable retaining strip formed with pointed longitudinal ribs which flatten into sealing engagement with the sash frame and glass pane when nails are driven therethrough to secure the strip in position.

25 A still further object of the invention is to provide a glass pane retaining strip which when in position imparts the appearance of putty, which may be secured in position by one unskilled in the art of a glazier, and which is inexpensive of construction.

With these and other objects in view, the invention resides in the certain features 30 which will be more apparent as the following specification is read in conjunction with the accompanying drawing, in which:

Figure 1 is a fragmentary sectional perspective view of a window sash with the invention in use thereon.

Figure 2 is a horizontal sectional view on the line 2-2 of Figure 1.

Figure 3 is a detail vertical sectional view through the base rail of a sash showing the 45 retaining strip about to be secured in position.

Figure 4 is a view similar to Figure 3 but showing the strip in secured position.

Figure 5 is a fragmentary sectional perspective view of the retaining strip.

Figure 6 is a detail cross sectional view through a slightly modified form.

Referring to the drawing by reference characters, the numeral 10 designates my improved window pane retaining strip which is substantially triangular shape in cross section, and constructed of a relatively soft malleable metal such as lead. The strip is formed with a relatively narrow width face 11 and formed centrally and extending lengthwise of the face 11 is a pointed rib 12, the said face on opposite sides of the rib being formed with channels or grooves 13. The rib 12 projects beyond the plane of the face 11 for a purpose to be presently explained. 55

The face 14 of the strip which is disposed at substantially right angles to the face 11 is wider than the said face 11 and is formed with a pair of spaced longitudinal pointed ribs 15, which ribs extend beyond the plane 60 of the face 14. Channels 16 are formed in the face 14 on opposite sides of the respective ribs 15. 65

The face or surface 17 of the strip is free 70 of ribs but openings 18 lead from the face 17 through the strip at an angle and open onto the face 14 as best seen in Figures 3 and 4 of the drawing.

In order to illustrate the invention, the strip is shown associated with an ordinary 75 type of window sash frame A, the same being provided with a rabbett B in which the edge of a glass pane C fits. Instead of filling the rabbets with putty as is the present custom, 80 a length of retaining strip 10 is cut to fit each side of the sash frame. The ends of the strip may be beveled so as to form tight joints at the corners of the frame and in the event 85 that a strip should be cut a length shorter than intended, the operator may by manually pulling upon the ends of the strip lengthen the same to the desired length. This lengthening of the strip is possible due to the 90 nature of the material from which the strip is formed, and assuming that the strip is molded in the shape shown, the lengthening of the same will in no way distort the cross sectional configuration. When the strip is of the proper length, it is inserted into the rabbett B with the face 11 fitting against the out- 95 100

side of the glass pane C and with the wider face 14 fitting against the wall of the rabbett in the sash A. The application of the strip to position is clearly shown in Figure 3, and it will be noted that the pointed rib 12 abuts the outer side of the glass pane whereas the ribs 15 abut the walls of the rabbett B. The operator then inserts nails or like fastening elements 19 through the openings 18 in 10 the strip and proceeds to drive the nails home into the sash frame. When the nails are driven home, the pounding applied by the hammer will cause the pointed ribs 15 to be flattened out against the wall of the rabbett B and will also cause the rib 12 to flatten out against the glass pane C. By the upsetting or smashing of the ribs, a positive seal is provided between the walls of the rabbett and the glass pane and the retaining strip to exclude the elements from passing to the inside of the window sash.

After the strips have been secured in position, the surface 17 may be painted and will in appearance resemble the putty now used as 25 a means for retaining a glass pane within the window sash.

In the event that the glass pane C should become broken and it is necessary to remove the retaining strip to replace the broken pane, 30 the ribs may be pointed up to their original position by the running of an implement along the channels or grooves 13 and 16. Thus it will be seen that the strips may be used over and over again in the replacement 35 of broken glass panes.

In Figure 6 of the drawing, a slightly modified form is shown wherein a single pointed rib 15' is formed on the face 14' in lieu of the double rib shown in the preceding 40 embodiment. The other parts are identical to the form shown in the other figures of the drawing.

While I have shown and described what I deem to be the most desirable embodiment of 45 my invention, I wish it to be understood that various changes as come within the scope of the appended claims may be resorted to if desired.

Having thus described the invention, what 50 I claim as new and desire to secure by Letters Patent of the United States, is:—

1. A window pane fastener comprising a strip of soft malleable material of substantially triangular shape in cross section, two 55 of the faces of said strip adapted to respectively fit against the glass pane and sash frame of a window sash, and longitudinal ribs extending the length of the strip on the above mentioned faces inwardly of the lon-

gitudinal edges thereof and projecting beyond the plane of said faces.

2. A window pane fastener comprising a strip of material substantially triangular shape in cross section and soft compressible ribs extending lengthwise on two of the faces of said strip inwardly of the longitudinal edges thereof and extending beyond the plane of the said faces thereof.

3. A window pane fastener comprising a strip of material substantially triangular shape in cross section, soft compressible pointed ribs extending lengthwise on two of the faces of said strip and extending beyond the plane of the said faces, and longitudinal grooves formed in said faces on opposite sides of said ribs.

4. A window pane fastener comprising a strip of lead of substantially triangular shape in cross section, and pointed projecting ribs extending lengthwise along two faces of said strip inwardly of the longitudinal edges thereof and adapted to flatten against the window pane and sash frame when secured in position by the driving of fastening elements through said strip into the sash frame from the other face thereof.

5. In a window pane retaining device, a strip of soft malleable material having a flat face, and a pointed rib formed integral with said strip inwardly of the longitudinal edges and extending beyond the plane of the flat face thereof.

6. A window pane fastener comprising a strip of malleable material substantially triangular shape in cross section to enable the free bending of the same and the drawing out of the strip without distorting its cross sectional contour to permit lengthening of the same if accidentally cut to a length short of a predetermined desired length, and pointed ribs formed on said strip and extending lengthwise of two side faces thereof and disposed beyond the plane of said side faces, the pointed ends of said ribs adapted to flatten against the window pane and sash frame when the fastener is in use.

7. A window pane fastener comprising a strip of malleable material having two right angularly disposed sides extending the length thereof, said strip in itself being freely bendable and capable of being lengthened by pulling outwardly upon the ends thereof if cut to a length short of a desired predetermined length, and distortable sealing means formed from and disposed on said right angularly disposed sides of said strip.

ANTON BREZINSKI.
